(57) **CLAIM**

The ornamental design for a sex toy, as shown and described.

DESCRIPTION

The patent or application file contains at least one drawing executed in color. Copies of this patent or patent application publication with color drawing(s) will be provided by the Office upon request and payment of the necessary fee.

Fig. 1.1 is a front view of a sex toy showing our new design;

Fig. 1.2 is a left bottom perspective view thereof;

Fig. 1.3 is a left top perspective view thereof;

Fig. 1.4 is a top perspective view thereof;

Fig. 1.5 is a bottom perspective view thereof;

Fig. 1.6 is a bottom plan view thereof;

Fig. 1.7 is a top perspective view thereof;

Fig. 1.8 is a top left perspective view thereof;

Fig. 1.9 is a top plan view thereof;

Fig. 1.10 is a left side view thereof;

Fig. 1.11 is a right side view thereof; and

Fig. 1.12 is a rear view thereof.
